UNITED STATES PATENT OFFICE

173,023

PORCH COLUMN

Winford L. Enghauser, Cincinnati, Ohio, assignor
to Enghauser Manufacturing Company, Inc., a
corporation of Ohio

Application September 29, 1953, Serial No. 27,001

Term of patent 14 years

(Cl. D54—2)

To all whom it may concern:

Be it known that I, Winford L. Enghauser, a citizen of the United States, residing at Cincinnati, in the county of Hamilton and State of Ohio, have invented a new, original, and ornamental Design for a Porch Column, of which the following is a specification, reference being had to the accompanying drawing, forming a part thereof.

Figure 1 is a front elevational view of a porch column showing my new invention.

Figure 2 is a side elevational view thereof.

I claim:

The ornamental design for a porch column substantially as shown.
